SIDE RAIL FOR AN AUTOMOBILE LUGGAGE RACK

James Stephen, Royal Oak, Mich., assignor to Helm Design & Manufacturing, Inc., Detroit, Mich., a corporation of Michigan

Filed July 26, 1968, Ser. No. 12,926

Term of patent 14 years

Int. Cl. D12—14

U.S. Cl. D14—27

FIG. 1 is a rear perspective view of a side rail for an automobile luggage rack embodying my novel design.

FIG. 2 is a top plan view of the same.

FIG. 3 is an outer side view of the same.

FIG. 4 is a sectional view on an enlarged scale taken along the line 4—4 in FIG. 2.

FIG. 5 is a sectional view on an enlarged scale taken along the line 5—5 in FIG. 2.

FIG. 6 is a front perspective view of the same.

The elements shown in broken lines are included for illustrative purposes only.

I claim:

The ornamental design for a side rail for an automobile luggage rack, as shown and described.
